HEEL CONSTRUCTION

Bayard Ryder, Los Angeles, Calif.

Application October 15, 1940, Serial No. 361,205

2 Claims. (Cl. 36—34)

In women's shoes it has long been conventional to employ wooden heels which are covered or surfaced in a variety of manners. Such heels are expensive because of the material employed, the complexity of the machinery required to form them in the desired shapes, and the necessity for skilled workmen to operate such machinery. It is an object of my invention to provide a heel construction of inexpensive materials and a method of forming this construction which requires neither intricate machinery nor skilled workmen.

Solid wooden heels contribute much undesired weight to women's shoes. It is an object of my invention to minimize the weight of the heel construction for women's shoes and more particularly to materially reduce the weight below that of conventional shoes by constructing the heel in the form of a hollow body.

It is the practice of most shoe manufacturers to purchase the wooden heels for women's footwear from others specializing in their production, thus requiring the manufacturer to maintain on hand substantial stocks of wooden heels of different styles, heights, and sizes to meet fluctuations in the demand for shoes of his manufacture. It is an object of my invention to provide a method of constructing heels for footwear which can be quickly performed by unskilled workmen in a small area of plant space and which thus eliminates the necessity of the maintenance of large stocks of preformed heels and reduces the cost of production of women's footwear.

The heel and the method of constructing it, which are the subject of my invention and which are capable of use in the production of footwear for men and children, as well as women, are described in the following specification, which may be better understood with reference to the accompanying drawing in which

Fig. 1 is a plan view of a pattern or outline of a sheet of material which may be employed in following the method of my invention;

Fig. 2 is a perspective view of the pattern of Fig. 1 applied to a form;

Fig. 3 is a perspective view of the finished heel of one embodiment of my invention;

Fig. 4 is a perspective view of a different embodiment of the heel of my invention;

Figs. 5 to 8, inclusive, are vertical sectional views of heels of my invention employing different reinforcing means; and

Fig. 9 is a vertical sectional view of an em-

bodiment of my invention adapted for use as a combined midsole and heel.

Referring to the drawing, which is for illustrative purposes only, the numeral 11 indicates a sheet of fibrous material; this fibrous material may be woven or structureless, such as matted and compressed felt. The sheet 11 is cut with downwardly diverging side boundaries 12 and 13, an upwardly curved upper boundary 14, and a lower boundary 15 substantially as shown. Triangular notches 16 having their apexes directed inwardly are cut from the upper boundary 14, and similar notches 17 are cut from the lower boundary 15 for a purpose which will be later described.

It is contemplated by the method of my invention that the sheet 11, either before or after it is cut to the outline illustrated in Fig. 1, shall be impregnated with a plastic in discrete form

20 or discontinuous phase as contrasted with a continuous phase. The plastic may be associated with the sheet 11 in a variety of ways. Thus a dope may be prepared, including, for example, cellulose acetate and a plasticizer, such as camphor or tricresyl phosphate, and a material to provide greater rigidity, such as gypsum, or calcium tartrate, or ammonium phosphate, in a solvent, preferably miscible with water, such as acetone or a mixture of acetone and alcohol. 25 The sheet 11 may be thoroughly impregnated with such a dope and then without drying passed through a bath of a character to precipitate the plastic in the goods. Water is a suitable bath if there is used the dope previously described. 30 In such a bath the plastic is in such condition that, when the fibrous sheet 11 is withdrawn from the bath and dried, it is soft and pliable. 35

Pyroxylin or cellulose nitrate may be employed instead of cellulose acetate. Fire retardants and 40 fillers other than gypsum, calcium tartrate, and ammonium phosphate may be employed.

The impregnation of the sheet of material 11 may also be accomplished, if desired, by emulsifying a dope, such as described, in water and 45 saturating the fabric sheet 11 in such emulsion.

Particles of plastic, for example, a mixture of cellulose acetate and camphor in solid form, may be mixed in the fibrous sheet 11 during its weaving or the compression and matting process, so 50 that these particles are positioned in or on the fibrous material and entangled and interlocked with the fibres thereof. Likewise the plastic in such particle form may be sprayed upon one or both surfaces of the fibrous sheet 11 so that 55 it adheres thereto and is impregnated therein.

It is possible also to secure the proper impregnation of the fibrous sheet 11 by immersing it in commercially available liquids containing plastics.

It is to be understood also that there may be employed in impregnating the fabric sheet 11 various natural gums and resins, or rosin or synthetic resinoids.

By any of the foregoing procedures or any other procedures desired, the fibrous sheet 11 is impregnated with a plastic of which the foregoing are only examples, which plastic is in such condition as to not detract materially from the flexibility of the fibrous material and which, when the fibrous material bearing it is wet with a solvent sufficient to render the material flaccid, gives to the fibrous material, upon evaporation of the solvent, stiffness and rigidity.

The particles of plastic may be also associated with the fibrous sheet 11 by securing to either or both sides thereof another sheet to hold the plastic particles in contact with the fibrous sheet as well as by precipitating or mixing, or spraying or applying the plastic in particle or other form in and upon the fibrous sheet, and I describe all such means of association of the plastic with the fibrous sheet to provide the pliability requisite to forming the sheet as impregnation.

The fibrous sheet 11, thus impregnated with plastic, is placed around a mold or form 18 which may be conveniently formed of wood with a shape in which it is desired to form the finished heel. The fibrous sheet 11 has been cut so that when it is applied to the form 18, the side boundaries 12 and 13 abut as indicated by the line 19 upon the breast surface of the heel. The lower portion of the fibrous sheet 11 is folded upon the bottom of the form 18 to form an inwardly directed flange 20, the edges of each triangular notch 17 meeting so that the flange 20 is uninterrupted, and the portions of the sheet 11 forming such flange do not overlap each other. The sheet 11 is held in this position in any suitable manner as by tacking through the sheet onto the form 18 adjacent the line 19 and tacking through the flange 20 into the form 18, and the form with the sheet 11 attached thereto is then immersed in a suitable solvent. The solvent may be of any suitable type for imparting flaccidity to the fibrous material and causing the plastic to become rigid and stiff throughout the fibrous material upon the evaporation thereof. For example, if cellulose acetate is employed, a solvent of acetone or acetone and alcohol is suitable. Gypsum as a fire retardant and filler is advantageously employed in the dope, since it is insoluble therein. The immersion of the fibrous sheet 11 and the form 18 in the solvent bath is performed quickly to prevent substantial removal of the plastic particles therein, and the form 18 and fibrous sheet 11 thereon are then removed from the solvent and permitted to dry. The drying period varies with the different dopes and solvents employed. I have found with the dope and solvent last described fifteen to thirty minutes is adequate.

After the fibrous sheet 11 has dried, the form 18 is removed therefrom. If it is desired to reinforce the heel member, narrow strips of the same material employed in the sheet 11 may be secured to the inner surface of the rigid hollow shell indicated by the numeral 21 of Fig. 3 after the removal of the form 18. Such a reenforcing strip may be placed upon the breast surface of the shell 21 over the line 19, as indicated by the dotted lines 22 of Fig. 3, or vertically in the rearward

portion of the shell 21, as indicated by the dotted lines 23 of the same figure, or vertically within the side portions of the shell 21, as indicated by the dotted lines 24. If required, such reenforcing strips may be placed on all of the surfaces indicated. In assembling such reenforcing strips, they are immersed in a solvent bath, such as previously described, and pressed against the inner surface of the hollow shell 21 in the desired position. The strips adhere to the hollow shell 21 and add to the rigidity thereof upon drying.

To provide means for attaching the shell 21 to a lasted upper and insole, the upper portion of the fibrous sheet 11 is turned inwardly to form an upper flange 25. The sides of each of the triangular openings 16 abut each other, thus providing a continuous flange of a single thickness of the sheet 11. If this upper portion of the sheet 11 was immersed in a solvent bath while the sheet 11 was applied to the form 18 with the result that it became rigid upon the evaporation of the solvent, it is necessary only to again wet it with the solvent to cause it to become flaccid and deformable to the desired shape.

A heel lift 26 of wear-resisting material, such as leather, is secured to the lower flange 20 of the shell 21. This attachment may be accomplished by tacks extending through the heel lift 26 and into the flange 20 or by the application of a suitable adhesive therebetween. The completed heel member is then ready for attachment to a lasted upper and insole either by tacks passing downwardly through the insole into the flange 25 or by the application of a suitable cement between the flange 25 and the lasted upper and insole.

Instead of extending the reenforcing strips substantially vertically, as indicated by the numerals 22 to 24, a single reenforcing strip, such as indicated by the numeral 27 of Fig. 4, may be secured to the inner wall of the shell 21 so that it extends spirally therein. The method of securing the reenforcing strip 27 in position is the same as that employed for securing the reenforcing strips 22 to 24 previously described.

Likewise, if desired, a reenforcing strip or plate 28 of the same material as the fibrous sheet 11 may be installed in a similar manner so that it connects the inner surface of the lower extremity of a wall portion of the shell 21 with the inner surface of the upper extremity of an opposite wall portion of the shell member as illustrated in Fig. 5.

Another form of reenforcing means is illustrated in Fig. 6, in which the numeral 29 indicates a plate formed of the same material as the fibrous sheet 11 secured in the manner previously described to the lower end of the shell 21. An upper plate 30 similarly secured to the upper end of the shell 21 may be employed either alone or with the lower plate 29. The plates 29 and 30 serve to both reinforce the shell 21 against distortion and provide additional area for securing the heel lift 26 and the lasted upper and insole respectively to the shell 21. The same effect may be secured by forming the fibrous sheet 11 of greater vertical dimension so that, when the portions thereof between the triangular notches 16 or 17 are folded towards each other, they complement each other in entirely covering the ends of the shell 21, as illustrated by the numeral 31 of Fig. 4.

Referring to Fig. 7, the numeral 32 indicates an upper, the lower edges of which are pulled

around and secured to the lower surface of an insole member 33. There is thus formed on the lower surface of the insole member 33 a depending flange 34 of a thickness equal to the thickness of the upper. To facilitate the firm attachment of a heel shell 21, having upon its upper end an inwardly directed flange 25, such a flange may be formed with a downwardly offset or lift portion 35 to receive the depending flange 34. By such provision the flange 25 of the shell 21 bears against and may be secured to both the inturned edge of the upper at the flange 34 and the lower surface of the insole 33 inwardly thereof.

If it is desired to provide additional rigidity to the shell 21, this may be accomplished by the provision of a post 36 secured to the heel lift 26 as by nails 37 and attached to the insole 33 as by a screw 38, the top of which is covered and cushioned by a slip sole or lining 39.

Resistance to horizontal as well as vertical deformation may be provided by the use of a vertical post, such as indicated by the numeral 40 of Fig. 8, which is secured to a reenforcing member 41, filling the lower part of the shell 21 and to a reenforcing member 42 filling the upper part of the shell 21. The posts 36 and 40 and the reenforcing members 41 and 42 may conveniently be made of wood. The lasted upper 32 and insole 33 and the top lift 26 may be conveniently secured to the upper and lower reenforcing members 41 and 42 respectively. Further, the provision of the lower reenforcing member 41 with its lower surface flush with the lower surface of the shell 21, protects the shell 21 as the heel lift 26 is worn away.

Referring to Fig. 9, there is illustrated a foot supporting element or member 43 which is interposed between a lasted upper 44 and an insole member 45, and a wear resisting outsole member 46. The foot supporting member 43 may be formed of fibrous material impregnated with a plastic such as the fibrous sheet 11 or of material which is flaccid or pliable with a plastic or plastic forming ingredients, such as previously described, positioned therein or thereon, either before or after it is molded upon a suitable form.

As in the embodiments previously described, the flaccid material may be positioned or tensioned upon a form with its lower portion turned inwardly upon the form to provide a lower flange 47. After the material has been stiffened by the deposition of the plastic therein, the form and the foot supporting member 43 are separated, and an upper flange 48 is formed thereon. If the upper portion of the foot supporting member 43 has become stiffened with the remainder thereof, this upper portion is again rendered flaccid, as previously described, thus permitting the formation of the substantially horizontal flange 48 and its subsequent stiffening by deposition of the plastic therein in a continuous phase.

The flanges 47 and 48, like the similar flanges in the embodiments previously described, may be made either continuous, extending completely around the periphery of the vertical walls from which they project, or in the form of tongues or arms as may be desired. Likewise the fibrous material of which the foot supporting element 43 is formed, like the heel constructions previously described, may be covered with a fabric or a coating, either before or after the material is formed into the desired shape, concealing the fibrous material and any plastic deposited upon its surface and enhancing the decorative effect

of the footwear. A pleasing effect can be secured also by embodying a pigment in the fibrous material of which the heel or foot supporting element is formed or weaving, dyeing, or coloring in any suitable manner a fabric to be employed as the fibrous material or by depositing upon the exterior surface of the fibrous material a layer of the plastic, colored or uncolored, simultaneously with, or subsequent to, or in lieu of the deposition of the plastic relied upon to stiffen the fibrous material.

The method and heel construction of my invention has great utility in such differing fields as orthopedic footwear, women's style footwear in which the heel constructions may be provided with notches or openings covered, if desired, with a decorative or transparent material, and infants' footwear, in which a device producing sound when the shoe is moved, may be installed in the hollow heel or intermediate foot supporting member 43 of Fig. 9.

With regard to all the heel constructions and foot supporting elements of my invention, it will be seen that, since they are shaped in hollow form and of comparatively thin light-weight material, I have by my invention provided foot supporting elements adapted for insertion between a lasted upper and outsole which are substantially lighter than prior constructions.

Further, since the method of my invention requires only the securing of a pliable sheet of material to a form and the deposition therein of a stiffening plastic which may be carried by the material, I have by my invention provided a method of forming heels and foot supporting elements for shoes which can be performed without the use of expensive or intricate machinery and which can be performed by unskilled workmen. Likewise, since the foot supporting elements of my invention may be quickly formed as needed, my invention eliminates the necessity of maintenance of large stocks of heels by manufacturers.

While those embodiments of my invention hereinbefore illustrated and described perform all the objects and provide all of the advantage primarily stated, it will be understood that there are various other embodiments likewise capable of performing these objects and providing these advantages and coming within the scope of my invention which are defined by the claims that follow.

I claim as my invention:

1. In a heel construction for a shoe, the combination of: a hollow shell of fabric impregnated with a rigid plastic; a first rigid reenforcing member within said shell and adjacent its upper end; a second rigid reenforcing member within said shell and adjacent its lower end; and a third rigid reenforcing member within said shell and connected to said first and second reenforcing members.

2. In a heel construction for a shoe, the combination of: a hollow shell of fibrous material impregnated with a rigid plastic; a first rigid reinforcing member secured within said shell and substantially closing its upper end; a second rigid reinforcing member secured within said shell and substantially closing its lower end; and a third rigid reinforcing member within said shell and connected to said first and second reinforcing members.
